UNITED STATES PATENT OFFICE

2,452,290

HYDRAULIC TORQUE CONVERSION
APPARATUS

Douglas L. Butow, Evanston, Ill.

Application November 2, 1945, Serial No. 626,296

3 Claims. (Cl. 60—54)

1

This invention relates to hydraulic torque conversion apparatus. The invention will be useful in the transmission of power from reciprocating means in motors of various types of rotating structures. A large variety of uses will be obvious.

An object of the invention is to provide simple and effective structure for hydraulic torque conversion through the means of a reciprocating driver or piston to a rotor structure. A further object is to provide means for controlling the delivery of power irrespective of the speed of the reciprocating driver or piston. Yet another object is to provide mechanism in which a plurality of hydraulic torque conversion units are employed for driving a rotor in opposite directions and for controlling the speed of the rotor. Other specific objects and advantages will appear as the specification proceeds.

The invention is illustrated in a preferred embodiment, by the accompanying drawing, in which—

Figure 1 is a longitudinal sectional view, the section being taken as indicated at line 1—1 of Fig. 3; Fig. 2, a broken sectional view showing the gate valve in lowered position; and Fig. 3, a top plan view of apparatus embodying a number of torque conversion units.

In the illustration given, A designates a casing which may be of any suitable construction. In the form illustrated, the casing provides an outer wall 10 and an inner wall 11 running parallel with the outer wall 10 on the lower side of the structure and providing a piston cylinder 12. 13 designates an outer casing which provides, with the casing 10, a release or control channel 14. The walls 10 and 13 are greatly expanded at one end to provide a rotor chamber 15. The inner wall 16 provides an outlet conduit 17 through which liquid from the rotor may return to a reservoir 18 provided also by the wall 13. The wall 16 merges at its lower end into the wall 11. A short wall 19 connects an intermediate portion of wall 16 and wall 11 to provide therebetween an open chamber 20 providing access to the gate valve, as will be later described.

The reservoir 18 may be provided with vanes 21 which decrease the turbulence of the liquid flowing back and increase the efficiency of the flow.

A shaft 22 extends through the side wall of the casing A and is provided with a crank 23 upon which is mounted the piston arm 24. Member 24 is connected at 25 with the open-ended piston 26. The piston 26 is open on its rear side at 27. It is similarly open at 28 on its front side, but is there controlled by a valve 29 pivotally secured to the piston at 30. The trap valve 29 permits the piston to go rearwardly through liquid, with liquid passing entirely through the opening 28,

2

but on its forward stroke the valve 29 prevents the flow of liquid through the piston 26.

Just forward of the piston 26, I provide a gate valve control member 31. The gate valve 31 extends through an opening in the wall 11 and through the wall 10. The valve is guided by members 32 and 33, as shown more clearly in Fig. 2. The valve 31 is provided centrally with an aperture 34, and at its bottom is provided with a closure member 35. The wall 10 is apertured at 36 to permit liquid to flow from the cylinder 12 into the channel 14.

Within the rotor chamber 15 is mounted a rotor 37 carried by shaft 38. The rotor is equipped on its periphery with vanes 39, as shown more clearly in Fig. 1.

The torque conversion units A may be arranged in any suitable manner. In the illustration given in Fig. 3, four of the units are arranged in a parallel arrangement, but two of the units are arranged in opposite directions so that they may tend to rotate the common shaft 38 in an opposite direction.

It will be understood that any means for manipulating separately gates 31 for each of the units or for manipulating them in groups may be employed.

The check valve 40 in cylinder 12 is pivoted to the wall 11 and preferably sealed along its free sides by the flange 41. The valve permits flow of liquid matter toward the vanes 39 during the power stroke of piston 26, but prevents back flow when piston 26 is being retracted.

In the operation of the structure, the shaft 35 22 is rotated by power means (not shown), and the crank 23 through the piston arm 24 causes the piston 26 to reciprocate. As the piston moves to the right, the valve 29 opens and liquid is free to pass therethrough. When, however, the piston is thrust forwardly, the valve 29 closes and provides a sealing closure for the front of the piston and liquid is forced under the power impulse forwardly against the vanes 39 of rotor 37. In normal operation, the gate valve 31 is in elevated position, as shown more clearly in Fig. 1, and allows the liquid to pass through the aperture 34 and against the vanes. The liquid flows upwardly around the rotor 37 and is discharged through the passage 17, flowing backwardly into the reservoir chamber 18, and from thence into the rear of the cylinder 12.

Should the operator desire to stop the operation of rotor 37 without stopping the power shaft 22, the gate valve 31 is dropped to the position shown in Fig. 2 and the liquid flows forwardly and then downwardly through the aperture 36 and through relief channel 14 back to the reservoir 18. In the latter operation, the upper portion of the gate valve 31 seals the cylinder passage 12, while the aperture 34 of the gate valve opens the passage

14. If a small amount of power is to be delivered to the vanes 39, the valve 31 is dropped partially so that only a portion of the liquid is permitted to escape through the release channel 14. Thus, effective and quick control is maintained upon the operation of the rotor 37, no matter how rapidly the shaft 22 may be operated.

It will be understood that the units A may be arranged in any sequence and in any order in order to obtain specific results. In the arrangement shown in Fig. 3, the two units A on the left-hand side of the structure will propel the common rotor shaft 38 in one direction, while the four units A on the righthand side of the structure will propel the rotor shaft 38 in the other direction. Thus, the structures may be balanced against each other as braking means or employed for the purpose of reversing the operation. For example, the four units A may drive the common shaft 38 in the usual direction to give forward speed, while the two units A on the opposite side may be employed for rotating shaft 38 in the opposite direction to give a reverse movement.

The check valve 40 operates in conjunction with the piston 26 permitting flow toward the vanes during the power stroke but preventing back flow of liquid matter toward the piston during the rearward stroke of the piston. This results in sealing the piston chamber when the piston is on the intake stroke and therefore relieves any back pressure created by the rotor vanes while the piston cylinder is receiving its charge of liquid matter.

In the structure shown in Fig. 3 where multiple units are employed, it will be noted, the common driver 22 may be connected to any suitable mechanism and the member 22 serves as a common drive shaft for all the units on the one side of the structure.

In the use of the term "liquid," herein, it will be understood that I intend to cover any liquid matter which may be employed for the effective operation of the structure described.

It will be understood that the structure shown is merely illustrative of the invention and that considerable variation may be made in the physical structure to produce efficient operation. Further, the details given may be modified widely by those skilled in the art without departing from the spirit of my invention.

I claim:

1. In hydraulic torque conversion apparatus, a casing providing a substantially straight piston conduit, an arcuate rotor chamber communicating on one side with the forward end of said conduit, and communicating on another side with a reservoir in communication with the rear end of said conduit, said casing also providing a passage outside of said rotor chamber leading from the forward end of said conduit and about said rotor chamber and communicating with said reservoir, a rotor member mounted in said rotor chamber and equipped with outwardly extending vanes, a casing member forming an extension of said casing providing said piston conduit and extending part-way around said rotor to provide between it and the rotor casing an intermediate passage establishing communication between said rotor chamber and said reservoir, a piston mounted for reciprocation in said conduit and having a passage therethrough equipped with a check valve, and means for reciprocating said piston, said

check valve opening said passage in the piston when said piston is drawn rearwardly and closing it when said piston is advanced.

2. In hydraulic torque conversion apparatus, a casing providing a piston conduit, a rotor chamber communicating therewith, a reservoir chamber connecting said rotor chamber and the inlet side of said conduit, a piston mounted for reciprocation in said conduit and having a passage therethrough, a check valve controlling said passage through said piston, means for reciprocating said piston, said valve allowing liquid to flow through said piston when the same is moved rearwardly and preventing flow therethrough when said piston is advanced, a check valve in said conduit between said piston and rotor chamber and allowing liquid to pass toward said chamber but preventing flow from said rotor chamber toward said piston and vanes extending upwardly and rearwardly in said reservoir chamber permitting the flow of liquid from said rotor chamber toward the rear end of said piston conduit but impeding the flow of liquid in the opposite direction when said piston is moved rearwardly.

3. In hydraulic torque conversion apparatus, a casing providing a piston conduit, a rotor chamber communicating with the forward end of said piston conduit, a return chamber connecting said rotor chamber and the rear end of said piston conduit, a piston mounted for reciprocation in said conduit and having a passage therethrough, a check valve mounted in said piston to prevent flow of liquid through said piston when said piston is advanced but to allow flow therethrough when said piston is drawn rearwardly, means for reciprocating said piston, casing means providing a conduit between the forward end of said piston passage and said return chamber, valve means controlling the flow of liquid through said last-mentioned conduit and the flow from said piston conduit to said rotor chamber, a rotor mounted in said chamber and equipped with vanes, a return conduit between said rotor chamber and said return chamber, and upwardly and rearwardly-extending vanes allowing flow of liquid through said return chamber toward the inlet of said piston conduit but obstructing flow of liquid in the opposite direction when said piston is being moved rearwardly.

50 DOUGLAS L. BUTOW.
